SOAP DISH

Frank D. Low, La Grange Park, Ill., assignor to
Hotpoint Inc., a corporation of New York

Application December 1, 1950, Serial No. 198,689

4 Claims. (Cl. 45—28)

1

This invention relates to an improved receptacle for soap and other cleaning materials or devices, and particularly to a ventilated receptacle which may be permanently secured within the backsplasher of a kitchen sink or the like.

Cover-provided soap receptacles are old in the art, but in the past have had generally inadequate provisions for admitting air in sufficient quantities to dry the soap cake, wash cloth or the like, which may have been placed therein immediately after use. It is therefore a particular object of my invention to provide a covered container—hereinafter for brevity referred to as a soap dish—having a closure member which provides concealed passages of large area through which air may enter and water and drippings escape to the sink.

It is another object of my invention to provide a soap dish having a bottom-hinged cover, the inner wall of which has rib formations which define large area openings for the admission of air into the soap dish when the cover is closed and yet are effective to prevent small articles, thin "slivers" of soap and the like, from escaping through the openings.

It is a further object of the invention to provide a soap dish having a bottom-hinged cover provided with ribs which when the cover is open define a substantially horizontal support for the soap cake, the wall portions between said ribs sloping downwardly to convey drainage away from said cake, whereby the cover may serve as a convenient and efficient shelf on which to place the soap cake during use.

Other features and advantages of my invention will be apparent from the following detailed description of the presently preferred embodiment illustrated in the accompanying drawings in which Fig. 1 is a front elevation of a soap dish embodying my invention, the cover being closed and the soap dish installed in the backsplasher of a sink; Fig. 2 is a side sectional elevation taken on lines 2—2 of Fig. 1; Fig. 3 is a similar side sectional elevation of the soap dish with the cover in open position; Fig. 4 is a plan section taken on lines 4—4 of Fig. 3; and Fig. 5 is an enlarged section taken on lines 5—5 of Fig. 4 showing a suitable hinge construction.

The illustrated embodiment of my invention has a box-like body 1 and a cover 2, either or both of which may advantageously be molded from polystyrene or other suitable plastic. The depth of the box is such as to take full advantage of the space within the backsplasher 3 of a kitchen sink or the like, the term "backsplasher" being com-

mon in the art to define the wall portion which extends upwardly behind the basin 4 of the sink. A front to rear dimension of about three inches is adaptable to most present day sinks, and the 5 inside width should be of the order of five inches to accommodate a laundry size soap cake. A peripheral flange 5 provides a neat finishing wall about the margin of the opening provided in the backsplasher. The side walls 6 of the box may 10 be pierced to provide slightly elongated openings which accommodate screws 7 to secure the box to conventional threaded devices 8 suitably secured to the inner backsplasher wall and extending appropriately therefrom. The bottom wall 9 of 15 the body slopes suitably toward the open front, for drainage.

Cover 2 is hinged to the box at the bottom thereof; the hinge may advantageously be of the simple snap-spring type shown in Rathbun U. S. 20 Patent No. 1,833,305 granted November 24, 1931. In such construction, hinge members 10 project from the bottom wall of the box adjacent the sides thereof, each hinge member providing relatively short, rounded, pivot pieces 11 which extend forwardly of an undercut central portion 12 within which seats the reentrant end of the hinge spring 14. The cover has female hinge elements 15 having concave forward wall portions for co-operation with the round nose pivots 11. As 25 shown in Fig. 5, the rear of the cover hinge element is also undercut to seat the opposite end of hinge spring 14. Side wall portions 16 engage the sides of the outermost walls of hinge elements 15 to stabilize the cover against twisting when 30 it is in its open position, although it will be appreciated that the relatively wide spring clips 14 contribute substantially to such stability because they are under tension when the cover is open and lie against the upper surfaces of the respective hinge elements. The spring clips have an inherent "overthrow" characteristic which causes 35 the cover to move between its open and closed positions with slight pressure on its handle 17. The side and top marginal walls of the cover seat 40 rather snugly against the forward surface of the side and top flanges 5 of the box 1, when in closed position. Short ribs 18 extending from the cover project slightly into the box and engage the inner top wall surface thereof to assist in establishing 45 and maintaining the proper alignment of the cover and body portions when the cover is closed.

It will be noted from Fig. 4 that the cover side walls 20 are substantially triangular; when the cover is closed its front wall slopes forwardly 50 away from the lowermost flange 5 leaving a rela-

tively wide air and drainage space 21 which extends almost the full width of the box 1. The lowermost edge 22 of the cover front wall extends downwardly beyond the side walls and effectively screens the opening 21 so that it is not visible to the adult of average height, who sees only the pleasing arrangement of Fig. 1 when the cover is closed. The inner wall of the cover is formed with spaced, substantially triangular, wall structures or ribs 23 which when the cover is closed assume an upright position in which the bottom walls 24 extend sufficiently close to the forward edge 25 of the box to prevent escape of small articles, thin soap cakes, etc., through the opening. It is obviously advantageous from the manufacturing aspect to form the ribs 23 integral with the cover and to have them imperforate; but they may be rodlike structures, suitably secured to the cover. In any event, and as appears in Fig. 4, the respective ribs are narrow and, therefore, will support a soap cake S with maximum air circulation about the bottom and sides of the cake. Drippings from the cake, or from scouring pads of other cleaning devices which may have been placed within the soap dish immediately after use, will drain out through the opening 21 into the sink bowl. When the cover is open, as in Fig. 3, the supporting edges of ribs 23 are approximately horizontal and in line with the supporting surfaces provided by the ribs 26 which extend upwardly from the sloping bottom wall 9. There is thus formed a convenient shelf on which the soap cake may be placed during use. The spring hinge clip 14, by engaging the upper surfaces of the hinge members 11 and 15, limits the downward movement of the cover; and by properly relating the extent of projection of the hinge members 11 with the length of the cover front wall and the angle at which the front wall projects from the backsplasher, I am able to maintain an adequate drip passage 27 which will accommodate the drainage from a soap cake or the like.

It will thus be seen that I have provided a soap dish or similar receptacle which provides ample drainage and air circulation about the soap cake when the receptacle is closed and in which the open cover offers a convenient supporting shelf with adequate drainage facilities. Whether open or closed, small articles such as articles of jewelry or the like may be placed in the box for safe keeping, or laid on the shelflike cover, while one is washing dishes or performing other tasks at the sink.

While there has been described what is at present considered to be the preferred embodiment of the invention, it will be understood that various modifications may be made therein, and it is intended to cover in the appended claims all such modifications as fall within the true spirit and scope of the invention.

I claim:

1. A receptacle for soaps and the like, comprising a box having a front opening and a bottom wall sloping downward toward said opening, a cover hingedly secured thereto at the bottom edge portion thereof, said cover having substantially triangular side walls which with the cover in closed position seat snugly against the side walls of the box and extend the front cover wall angularly outwardly from the top of the box into spaced relationship with the bottom edge thereof to provide a relatively wide bottom opening comprehending a major portion of the box width for admission of air to the interior of the box, a plurality of spaced, relatively narrow, ribs projecting upwardly from the bottom wall of the box to position the top edges thereof in a substantially horizontal plane, and a plurality of spaced ribs projecting inwardly from the front cover wall and extending substantially from the top to the bottom thereof, said ribs when the cover is opened presenting substantially horizontally disposed upper edge surfaces in approximate alignment with the edge surfaces of said box wall ribs whereby said ribs respectively cooperate to provide a ventilated shelf on which a cake of soap or the like may be placed during use.

2. A receptacle for soaps and the like, comprising a box having a front opening and a cover hingedly secured thereto at the bottom edge portion thereof, said cover having wall means which with the cover in closed position abut adjacent walls of the box and extend the front cover wall angularly outwardly from the top of the box into spaced relationship with the bottom edge thereof to provide a relatively wide bottom opening comprehending a major portion of the box width for admission of air to the interior of the box when the cover is in closed position, means for establishing a uniform open position of the cover with the bottom edge of said cover spaced forwardly of and below the bottom edge of the box, and a plurality of spaced, relatively narrow, wall structures integral with said front cover wall and projecting inwardly therefrom, said wall structures extending substantially from the top to the bottom thereof and the upper edges thereof forming a structure for supporting a cake of soap or the like above the cover wall when the cover is in said open position.

3. A receptacle for soaps and the like, comprising a box having a front opening and a bottom wall sloping downward toward the bottom margin of said opening, a cover hingedly secured thereto at the bottom edge portion thereof, said cover having substantially triangular side walls which with the cover in closed position seat snugly against the side walls of the box and extend the front cover wall angularly outwardly from the top of the box into spaced relationship with the bottom edge thereof to provide a relatively wide bottom opening comprehending a major portion of the box width for admission of air to the interior of the box when the cover is closed, and a plurality of spaced, relatively narrow, ribs projecting inwardly from the front cover wall and extending substantially from the top to the bottom thereof to form substantially vertical guard members extending into relatively close proximity to the forward edge of the bottom wall of the box when the cover is closed.

4. A soap receptacle, comprising a box having a front opening and a bottom wall sloping toward the bottom front edge thereof, a plurality of upstanding wall structures disposed in relatively closely spaced relation on said bottom wall and extending from front to rear thereof to form support means for a cake of soap or the like, a cover wall for the front opening of said box, hinge means for securing said cover wall to said box to permit the cover to be swung downwardly into open position, the axis of rotation of said hinge means being disposed intermediate the respective bottom edges of said cover wall and said box opening to position the lower edge of said cover wall, when the same is in closed position, forwardly of the bottom front edge of said box to provide a space extending substantially the length of said

box for the admission of air thereinto, and means for establishing the open position of said cover to permit the same to be used as a shelf for the support of said soap cake, said cover wall when in said open position draining toward a drip opening disposed forwardly of said box.
